BAG HEADER

Robert F. Windstrup, Edward Rose, and Nicholas S. Miller, Chicago, Ill., assignors to Peters Machinery Company, Chicago, Ill., a corporation of Illinois

Application April 9, 1956, Serial No. 576,848

16 Claims. (Cl. 53—14)

This invention relates generally to a bag header, and more particularly to a novel machine for automatically applying and heat-sealing header labels to gusset-type cellophane bags.

In the packaging of food products and other goods into gusset type cellophane bags, it has formerly been necessary to employ costly hand operations in order to complete the packaging operation.

It is a primary object of the present invention, therefore, to provide a fully automatic machine to receive filled open-end bags upon a conveyor, move such bags in a continuous timed sequence and in successive series through the machine to tuck the gusset, apply the header label, heat-seal both the bag and the header, apply a code or date to the header, and discharge the sealed package.

It is another object of this invention to provide a fully automatic bag header capable of high-speed operation up to 70 bags per minute, and capable of producing neater and more uniform packages than are possible with hand or semi-automatic operations.

It is a further object to provide a fully automatic bag header readily adapted for adjustment to accommodate filled bags and headers under substantially the entire range of sizes for commercial packaging with cellophane bags, including filled bags from $1\frac{1}{4}$ to $2\frac{3}{4}$ inches in thickness, 2 to $5\frac{1}{4}$ inches in length, and 6 to 12 inches in height.

It is still another object to provide in combination with means for automatically effecting combined gusset-tucking and sealing of cellophane bags at a single operating station, novel means for automatically applying and folding a header label over the closed end of the bag.

It is still a further object to provide novel means for applying and folding a header label over the closed end of a cellophane bag, and for effecting heat-sealed attachment thereto at a single operating station.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawings, in which:

Figure 1 is a top plan view, with parts broken away and removed to show details of construction, of a bag header machine constructed in accordance with the present invention;

Figure 2 is a side elevational view, with parts broken away and removed, of the machine shown in Figure 1;

Figure 42 is a side elevational view showing a modified form of label feeding magazine; and

Figure 43 is a timing chart showing the relative sequential movements of the various operating mechanisms of the machine.

Before describing the present invention in specific structural detail with reference to the drawings, we will briefly describe the sequence of operations automatically effected by our novel bag header. In this way, the various structural means utilized for feeding a series of filled and open cellophane bags onto an indexing conveyor, tucking the gussets, pre-sealing the bag, applying the header label and tack-sealing it to the bag, final-sealing the header label and bag, applying a code or date stamp to the header label, and effecting discharge onto a take-away conveyor, may be more readily understood.

For purposes of briefly describing the over-all functional operation of our bag header, reference may be made to Figure 1 of the drawing wherein the sequence of successive machine operations during movement of a bag from the inlet end to the outlet end of the machine. Seven distinct operations are performed by our machine in successive sequence as a filled bag is carried from the inlet end to the outlet end and discharged as a sealed and labeled final package. In practice, bags of cellophane or like flexible thermoplastic material are employed, so that the bags may be readily sealed upon application of suitable heat and pressure. It will be understood, of course, that other pressure sensitive or glue coated material can be utilized without changing the basic operation of the machine disclosed by the present invention.

The letter A designates a feed or loading station where the bag is transferred from an inlet conveyor onto a main indexing conveyor. The bag is moved intermittently forwardly by the main conveyor to a gusset tucking station, indicated at B. At Station B a tucking mechanism effects a tucking of the gussets on both sides of the bag, after which a first sealing means closes on the bag to effect a heat pre-sealing thereof. The bag is then moved to Station C where additional heat pre-sealing means operate to further tack-seal the top of the bag in closed relation. At Station D a header label is folded over the bag and cooperating sealing means operate to seal the bottom edges of the header to the bag. The bag next moves to an idler station to provide a movement delay which enables a more efficient spacing of the various operating mechanisms of the machine. The bag is then moved to Station F where further sealing means effects a final-sealing of the header and the bag. The bag is then moved to the last station where a code or date is stamped onto the header, and the sealed bag is discharged onto a takeaway conveyor for removal from the machine. The detailed mechanical structure for performing each of the sequence of seven operations will now be described in detail with particular reference to the drawings.

Referring now more particularly to the drawings, we will describe in detail the supporting structure upon which the mechanical operating and driving mechanisms of our machine are supported. As best seen in Figure 2 of the drawing, we have indicated generally at 10 a main frame, including horizontal channel ties 12 and vertical channel legs 14. A plurality of top plates 16 are interconnected

to provide a unitary top surface integral with the main frame 10.

A super-structure support channel 18 (see Figures 4 and 7) extends horizontally across the machine above the top plates 16. The channel 18 extends from end to end along the length of the machine and is positioned in inverted relation upon a plurality of support housings 20 (see Figure 4). The channel 18 is rigidly secured to the top surfaces of the support housings 20 by connector bolts 21. The support housings 20 are simultaneously vertically adjustable to permit predetermined variable positioning of the support channel 18 at a desired location above the top plates 16. As will hereinafter appear, the channel 18 constitutes a fixed point of support for the various operating mechanisms which perform a sequence of operations upon a bag as it is carried through the machine. It is a highly important feature of this invention, therefore, to enable the support channel 18 to be readily adjusted to a desired vertical position relative to the particular height of the bags upon which the machine is to perform.

For this purpose, we provide an elevator mechanism to effect vertical adjustment of the support housings 20 and the channel 18 carried thereby. An elevator bushing 22 is provided within the lower end of each of the support housings 20, and is internally screw-threaded to receive the upper end of an elevator screw 24. A retainer sleeve 26 is fixedly carried by the elevator screw 24, and extends through a suitable aperture 27 in the top plates 16. The screw 24 integrally provides a shaft portion 28 at its lower end. The shaft 28 extends through a bearing sleeve 30 which is fixedly secured to a horizontal channel tie 12 of the main frame 10. A thrust bearing 32 is interposed between the upper end of the bearing sleeve 30 and the lower end of the retainer sleeve 26. The lower end of the shaft portion 28 of each screw 24 carries a sprocket 34. The sprockets 34, corresponding to the respective housings 20 thereabove, are adapted to be simultaneously driven by a suitable link chain in a manner to be hereinafter described in detail. In this way, the elevator screws 24 are axially fixedly supported upon the machine in a manner permitting channel-adjusting rotary movement.

In order to facilitate smooth and uniform vertical movement of the channel 18 when the screws 24 are rotated to effect vertical shifting of the support housings 20, a plurality of guide bars 36 are provided. Each guide bar 36 is fixedly secured at its upper end by means of an integrally attached bracket 38 to the channel 18. The lower end of each guide bar 36 is slidably received within a guide bracket 40 which is fixedly secured by means of a mounting flange portion 42 to the top plates 16. A lock screw 44 is provided for cooperation with each guide bar 36 to permit releasable fixed positioning of the channel 18 when set at a desired vertical height.

An inlet conveyor apparatus is indicated generally at 50 (see Figures 1 and 2) at the left-hand or inlet end of the machine. A supporting frame extension platform 52 extends from the main frame 10 and provides a supporting surface contiguous with the top plates 16. A conveyor belt 54 provides a horizontal traveling surface substantially at the level of the platform 52 and plates 16. As best seen in Figure 3 of the drawing, the conveyor belt 54 is supported at its opposite ends upon a driver pulley 56 and a driven pulley 58. The driven pulley 58 may be mounted for take-up movement relative to the driver pulley 56, in conventional manner, to adjust the tension of the belt 54 as desired. A drive shaft 60 rotatably mounts the driver pulley 56, and a driven shaft 62 rotatably mounts the driven pulley 58. Suitable pillow blocks and bearings carried by the platform 52 serve to rotatably support the shafts 60 and 62 upon the machine frame.

The drive shaft 60 carries a driven sprocket 64, adapted to cooperate with a link chain, as will be hereinafter described in detail, for effecting driving rotation of the shaft

60 for continuous forward movement of the belt 54 in the direction indicated by the arrows on Figure 3.

A pair of spaced vertical conveyor belts 66 and 68 are positioned at opposite sides of the horizontal conveyor belt 54 in parallel relation thereto. The belt 68 is of substantially greater length than the belt 66. Belt drive rollers 70 and 72, mounted for vertical rotation upon driver shafts suitably mounted in bearing supports upon the platform 52, are provided at the inward ends of the belts 66 and 68. Cooperating driven rollers 74 and 76 are provided at the opposite ends of the belts 66 and 68, respectively. The rollers 74 and 76 may be mounted for adjusting movement relative to the rollers 70 and 72, in the well-known manner, for the purpose of effecting take-up of the belt tension as desired. Driven sprockets 78 and 80 are carried by the belt drive rollers 70 and 72 at their lower ends, and are adapted to be driven, in a manner to be hereinafter described, to effect conveyor movement of the belts 66 and 68 in a forward direction.

Vertical abutment brackets 82 and 84 (see Figures 9 and 10) are provided within the belts 66 and 68 immediately adjacent the horizontal conveyor belt 54. The brackets 82 and 84 are fixedly mounted upon bearing support platforms 86 and 88, which are secured to the extension platform 52 and the top plates 16. Cooperating adjusting screws and slots 90 permit lateral adjusted positioning of the platforms 86 and 88 relative to the horizontal conveyor 54. In this way, the spacing between the vertical conveyor belts 66 and 68 may be adjusted to accommodate a particular bag width, and to insure thereby the positive gripping engagement of bags by the belts 66 and 68 when passing between the abutment brackets 82 and 84.

An elongated guide plate 92 (see Figure 13) is disposed inwardly beyond the belt 66, and provides a vertical surface in alignment with the driving surface of the belt 66, thereby effecting a guiding extension for bags, when carried beyond the vertical conveyor belt 66 by driving movement of both the horizontal conveyor 54 and the extended length portion of the longer vertical conveyor belt 68.

When the bags carried by the inlet conveyor apparatus are discharged at the forward end thereof, they are received at the loading station A (see Figure 1). A laterally reciprocable pusher plate 100 (see Figures 11-13) is provided in vertical linear alignment with the conveyor belt 68. The pusher plate 100 is of generally right angular shape so as to provide a multiple-fingered pusher portion 100a, and an abutment or stop portion 100b. The pusher plate 100 provides an integral mounting flange portion 101 at its lower end. It will be apparent that when a bag is discharged from the conveyor apparatus onto the loading station, the pusher 100a engages the adjacent side of the bag to effect lateral movement thereof toward the main conveyor. When the pusher plate 100 is moved laterally, the stop portion 100b serves to engage the next succeeding bag and prevent movement thereof onto the loading station until return movement of the plate 100 is completed.

A bag stop plate 102 is disposed directly in the path of the bags discharged from the inlet conveyor apparatus onto the loading station. The stop plate 102 provides a multiple-fingered abutment or stop portion 102a substantially at right angles to and cooperatively meshed with the pusher 100a. The plate 102 includes a mounting flange portion 103 at its upper end. (See Figure 12.)

The mounting flange portion 101 of the pusher plate 100 is provided with adjusting slots and cooperating screws 104 to permit adjustable fixed attachment of the pusher plate 100 to a carrier plate 106. The carrier plate 106 is fixedly mounted upon a slider bar 108. The slider bar 108 is mounted for reciprocating movement in a lateral direction upon a pair of spaced guide rails 110 and 112 (see Figures 14 and 15), which are fixedly mounted to the machine top plates 16.

As best seen in Figure 12, a connector bar 114 mounts a stop finger 115 in general alignment with and slightly beyond the stop 102a. The connector bar 114 is pivotally secured to a pivot bar 116 by means of a pin 117. A trip arm 118 is carried by the connector bar 114 for cooperation with a micro-switch 120 secured to a mounting plate 122. A bag stop bracket 124 provides a mounting flange portion 125 for fixed attachment to the top plates 116, and serves both to carry the mounting plate 122 and to provide an abutment against which the outward end of the bag stop 102a is adapted to engage (as seen in Figure 13).

A guide plate 126 is carried by the bag stop bracket 124. The bracket 124 and the plate 126 are each provided with elongated adjusting slots 128 for cooperation with attaching screws 129, so that the bag stop plate 102 may be adjusted relative to the pusher plate 100. The meshed finger portions of the plates enable substantial independent movement of the plate 102 relative to the plate 100. In this way, the effective width of the pusher 100a may be varied to accommodate bags of various widths.

The pivotal mounting of the stop finger 115 beyond the bag stop plate 102 enables a rotation of the stop finger 115 about a vertical axis when engaged by a bag fed onto the loading station, as indicated by the directional arrow in Figure 13. It will be apparent, therefore, that the feeding of a bag onto the loading station A, and its engagement against the stop finger 115, results in a pivotal movement about the pin 117 so as to effect contacting engagement of the trip arm 118 against the micro-switch 120. The micro-switch 120 thereby records the presence of a bag at the loading station for regulating the lateral feeding movement of the pusher plate 100 in timed sequence with the movement of the flights of a main indexing conveyor 150 (see Figure 1), as will be hereinafter described in detail.

The main indexing conveyor 150 includes an upper pair of continuous roller link chains, first chain 152 and second chain 153, and a lower pair of continuous roller link chains, first chain 154 and second chain 155 (see Figure 4). First chain 152 overlies second chain 153, and first chain 154 overlies second chain 155. Rotating centers for these chains are provided at opposite ends of the machine by a splined inlet end shaft 156 and a splined discharge end shaft 158. The inlet end shaft 156 extends vertically between the support channel 18 and the top plates 16. A thrust bearing 160 is supported in a recess on the top plates 16, and the shaft 156 extends therethrough. An idler sprocket 162 is rotatably carried by means of a bearing sleeve on the shaft 156, and is supported upon the thrust bearing 160. A drive sprocket 164 is fixedly connected to the shaft 156 immediately above the idler sprocket 162.

A hub 166 extends over the upper end of the shaft 156 and is supported by means of a bearing plate 168 upon a thrust bearing 170 which rests upon the top surface of the support channel 18. A bearing sleeve 172 surrounds the hub 166 and is fixedly secured to the channel 18. A sprocket 174 is keyed to a flange portion of the hub 166, and rests upon an idler sprocket 176 therebelow. A support plate 178 fixes the sprockets in predetermined vertical position upon the shaft 156.

A bearing assembly 180 is provided below the top plates 16, and a lower unsplined end 182 of the shaft 156 extends therethrough. The shaft end 182 is received in a housing 184, which provides an integral sprocket portion 186. A gear 188 is secured to the shaft end 182 by means of a thrust ring portion 190. As best seen in Figure 5, an adjustable worm 192 cooperates with the gear 188 to effect rotation of the shaft 156 relative to the housing 184. A lock screw 194 serves to fixedly secure the worm 192 in meshed cooperation with the gear 188, thereby rigidly coupling the housing 184 to the shaft 156. In this way, driving rotation of the

sprocket 186 serves to effect rotation of the shaft 156, but the shaft 156 may be adjustably rotated to change its position of adjustment relative to the housing 184.

The splined shaft 158 at the outlet end of the machine is vertically disposed in parallel relation to the shaft 156, and extends through a thrust bearing 200 supported upon the top plates 16. An idler sprocket 202 is rotatably carried upon the shaft 158, and a drive sprocket 204 is fixedly secured to the shaft therebelow. A hub 206 surrounds the upper end of the shaft 158 and is supported upon the channel 18 by means of a bearing plate 208 and a thrust bearing 210. A bearing sleeve 212 surrounds the hub 206 and is carried by the channel 18. A sprocket 214 is fixedly carried by the hub 206 at its lower end, as by welding, and supports thereabove an idler sprocket 216.

Take-up brackets 218 and 220 are provided in operative association with the shaft 158 for adjusting the longitudinal distance between the two shafts 156 and 158. Suitable elongated slots and connector bolts 222 provide adjustable fixed assembly of the bracket 218 with the channel 18 and the hub 206. In this way, slack in the pairs of link chains carried and driven by the various sprockets may be taken up.

A bearing assembly 224 is carried by a suitable mounting plate 225 of the main frame 10, and receives an unsplined end 226 of the shaft 158 therethrough. The shaft end 226 is received within a housing 228 and is fixedly secured thereto in adjustable manner by means of arcuate slots and bolts 234 (see Figure 6). The housing 228 integrally provides a sprocket 230 for cooperation with a continuous link chain meshed with the sprocket 186, and a sprocket 232 for cooperation with a link chain to receive driving power. In this way, rotation of the sprocket 232 will effect simultaneous rotation through the sprockets 230 and 186 of the splined shafts 158 and 156. It will be apparent that the splined shafts 156 and 158, and the cooperating slidably mounting of related driven elements serves to facilitate vertical adjustment of the main channel 18 without the removal of parts.

The pairs of link chains 152, 153, and 154, 155 serve to carry a series of bag pushers for moving a successive series of bags from the inlet end of the machine to the outlet end. The bag pushers include a rear upper series 250 and a rear lower series 252, slidably movable along continuous upper and lower guide rails 258 and 260 respectively (see Figures 7 and 17-18). A front upper series 254 and a front lower series 256 are similarly mounted for movement along the rails 258 and 260. The rear pushers engage the bags at the upper and lower ends of their trailing edge surface, and move them forwardly along the machine. The front pushers likewise engage the bags at the top and bottom, but function only as supports for the leading edge surface of the bags. It is necessary to adjust the space between the rear and front pushers to enable the machine to accommodate bags of varying sizes. It is desirable to provide about $\frac{1}{8}$ inch over-all clearance between each bag and the carrying pair of pushers at either side thereof. In this way, the bag position may be closely controlled at each operating station of the machine.

The rear pushers, upper series 250 and lower series 252, are simultaneously adjustable in either a forward or rearward direction upon rotation of the splined shaft 158 at the discharge end of the machine by means of the slots and bolts 234. In this way, the upper rear pushers 250 carried by the upper second chain 153, and the lower rear pushers 252 carried by the lower second chain 155, are moved simultaneously by means of fixed sprockets 214 and 204, respectively, when the shaft 158 is rotated and the shaft 156 remains stationary.

The front pushers, upper series 254 and lower series 256, are simultaneously adjustable in either a forward or rearward direction to provide a desired predetermined spacing between the front and rear pushers to suit the

particular bag size to be handled by the machine. In order to adjust the front pushers, it is necessary to effect rotation of the splined shaft 156 at the inlet end of the machine by releasing the set screw 194 in the housing 184 and rotating the worm 192. In this way, the upper front pushers 254 carried by the link chain 152, and the lower front pushers 256 carried by the link chain 154, may be moved simultaneously relative to the upper and lower rear pushers respectively, as desired, by rotation of the shaft 156, and the fixed sprockets 174 and 164 carried thereby, relative to the stationary shaft 158.

Through the use of separate pairs of chains for the front and rear pushers at both the upper and lower ends of the shafts 156 and 158, together with alternate fixed and idler sprockets carried by each shaft for cooperation with the chains, it is possible to effect independent alternative adjustment of both the rear series of pushers and the front series of pushers. In practice, the rear series of pushers are first adjusted for appropriate positioning of the bags moved thereby relative to the several operating stations of the machine. Thereafter, the adjusted position of the rear pushers will ordinarily remain the same for all machine operation with all bag sizes. The front series of pushers may then be adjusted toward or away from the rear series to enable machine operation with bags of various widths, as required.

Additional upper and lower inner guide rails 262, 263, and outer guide rails 264, 265 are provided along the front of the machine for slidably supporting the bags as they are carried by the conveyor (see Figure 7). An inner pair of vertical rods 266 and an outer pair 268 serve to adjustably support the inner rails 262, 263 and the outer rails 264, 265 relative to the channel 18. Brackets 270 enable adjustment of the inner rails toward and away from the channel 18. Similarly, brackets 272 and extension slides 274 permit adjustment of the outer rails toward and away from the channel 18. The vertical rods and cooperating tie brackets are vertically slidably relative to each other to facilitate vertical adjustment of the height of the channel 18 above the plates 16 without removing the rails. The bag guides may be readily positioned for bags of various widths, and will automatically adjust for bags of various heights together with the main channel 18.

It will be apparent that the main indexing conveyor 150 will serve to move a series of successive bags from the inlet end of the machine to the discharge end of the machine, and thereby through the successive operating stations B through G of the machine (as indicated in Figure 1). The operating structure at station B, which serves to effect bag tucking, or the formation of a "gusset," and bag heat pre-sealing will now be described in detail. The mechanical structure at each of the successive machine stations will thereafter be described in sequence of bag travel through the machine.

A source of driving or operating power for all of the stations is provided by a main cam power shaft 300 (clearly indicated in Figures 1 to 4), which extends from the inlet to the discharge end of the machine. The shaft 300 is supported for rotation at the discharge end of the machine by a bearing assembly 302 (see Figures 2 and 4). A support bracket or housing fixedly carried by the main channel 18 serves to position the bearing assembly 302, and thereby predetermines the location of the discharge end of the shaft 300 relative to the vertically adjustable channel 18. A beveled gear 306 is carried by the discharge end of the shaft 300, and cooperates with a second beveled gear 308 which is slidably carried by the elongated splined upper end 310 of a vertically disposed drive shaft 312. A bearing assembly 314 mounts the shaft end 310 for rotation. It will be apparent that the splined shaft end 310 serves to accommodate vertical adjustment positioning of the channel 18 and cam shaft 300 while maintaining interconnection of the beveled gears 306 and 308.

The lower end of the shaft 312 is rotatably supported by a bearing assembly 316 carried by the mounting plate 225 of the main frame 10. The lower end of the shaft 312 extends through a gear housing 318 therebelow, for transmission connection to a Geneva gear 320 (see Figure 3). The Geneva gear is mounted by means of a vertical shaft 322 having a sprocket 324. A suitable continuous link chain serves to couple the sprocket 324 with the sprocket 232 of the main conveyor chain drive shaft 158. In this way, driving rotation of the shaft 312 serves to effect indexing drive of the conveyor shafts 156 and 158, and thereby the main indexing conveyor 150. The lowermost end of the shaft 312 terminates within a gear box or speed reducer 326, from which driving power is received.

Referring now more particularly to Figures 19 through 21 of the drawing, a vertically reciprocable carriage plate 330 is slidably mounted between a pair of plates 332 and 334, which serve to carry a pair of vertical slides 336 and 337 for cooperation with suitably recessed and rearwardly extending flanged portions 338 and 339 of the carriage 330. A pair of pivot assemblies 340 (indicated in dotted lines on Figures 19 and 20) are rotatably secured to the flanges 338 and 339. Connector rods 342 and 344, adjustable for varying their vertical heights, are rotatably carried by the pivot assemblies 340 and extend upwardly for pivotal connection to a pair of lever arms 346 and 348. The arms 346 and 348 are fixed at their opposite ends to an operating shaft 350 rotatably carried within bearing blocks 351 mounted upon the plates 332 and 334. A tension spring 352 is secured to the arm 346 and to a fixed point on the machine frame for exerting a biasing force tending to move the connector rods 342 and 344, and thereby the carriage 330, in a downward direction. In this way, the carriage 330 is normally biased toward a predetermined lower position.

A cam roller 354 is carried by the arm 346 intermediate its ends, and cooperates with a tucker lift cam 356 which is rotatably driven by the cam power shaft 300. The arms 346 and 348 are fixedly secured to the shaft 350, so that when the lift cam 356 is rotated the arms 346 and 348 will be oscillated about the shaft axis 350, thereby raising and lowering the connector rods 342 and 344. In this way, the carriage 330 may be raised and lowered in accordance with a predetermined operating cycle controlled by the shape of the lift cam 356.

The carriage 330 serves to carry a pair of tucker finger assembly plates 360 and 362. (One of these assemblies will be described in detail, and the other assembly, which is structurally identical but in complementary form, will be designated in the drawings by the same numerals primed.) Each tucker finger assembly comprises an inside tucking finger 364 and an outside tucking finger 366. The inside finger 364 is bifurcated for meshing cooperation with the outside finger 366, thereby enabling the fingers to be crossed over with each outside finger passing through and slightly beyond the cooperating split inside finger. This functional inter-relation is clearly seen in Figures 24 and 27 of the drawing which show the fingers in crossed over relation to effect the formation of a "gusset" at the top of an open bag.

The tucking fingers 364 and 366 are rigidly carried by rotatable pivot shafts 368 and 370. The pivot shafts also rigidly carry a pair of cooperating cams 372 and 374. A latch lever 376 is pivoted to the assembly plate 360 adjacent the cam 372. The cam 372 and the latch lever 376 are formed with cooperating lock shoulders 372a and 376a, respectively. The cam 372 and the cam 374 are also formed with cooperating lock shoulders 372b and 374b. A tension spring 378 serves to bias the latch lever 376 in a counter-clockwise direction, as seen in Figures 23 to 26. A trip portion 380 of the lever 376 extends outwardly beyond the plate 360.

Torsion springs 382 and 384 serve to bias the cams 372 and 374 in counter-clockwise and clockwise directions,

respectively, as best seen in Figures 25 and 26. A limit bar 386 is carried by the cam 372 and is adapted to cooperate with a stop screw and bracket assembly 388 which may be adjustably positioned for limiting abutment of the bar 386 thereagainst. A limit screw 390 is similarly carried by the cam 374, and cooperates with a stop plate 392 which may be adjustably positioned by means of a slot and bolt 394. In this way, the extent of "over-lap" when the fingers are crossed-over into meshed relation may be varied to provide a "gusset" of desired depth.

The normal rest position of parts is indicated in Figure 25, wherein the latch lever 376 and cam 372 effect cooperative abutment of the shoulders 376a and 372a for limiting the rotation of the cam 372 in a counter-clockwise direction. Similarly, abutment of the shoulders 372b and 374b prevents clockwise rotation of the cam 374.

A trip shoulder 398 is provided by the template 332, and is adapted to be engaged by the latch trip 380 as the carriage 330 is lowered downwardly. Such engagement is indicated in Figure 26, wherein the latch shoulder 376a is rotated clockwise against the bias of spring 378 and moved out of engagement with the cam shoulder 372a, thereby permitting rotation of the cam 372 and its pivot shaft 368 in a counter-clockwise direction until limited by engagement of the bar 386 with the stop screw 388. In the same way, the shoulders 372b and 374b of the cams are separated to enable clockwise rotation of the cam 374 and its pivot shaft 370 until limited by engagement of the screw 390 against the plate 392.

The carriage 330 provides a pair of elongated horizontal adjustment slots 396, for bolted mounting of the assembly plates 360 and 362, thereby enabling adjusted positioning of the spacing distances between the two plates. In this way, the pairs of tucking fingers may be properly positioned for operation with bags of various widths. A trip bar 400 of elongated form is adjustably carried by the template 334 for positioning below the latch lever trip 380' of the assembly plate 362.

Reset means for returning the tucking fingers to their normally spaced positions after actuation by release of the latch levers 380 and 380' is provided by a pair of reset rollers 402 and 402', rotatably carried by a pair of arms 404 and 404' which are fixedly secured to the corresponding pivot shafts 368 and 368'. A reset actuator plate 406 is carried by a shroud or housing 407 (see Figure 20), which overlies the tucking mechanism.

In practical operation, the carriage 330 is moved downwardly in timed sequence with the presence of a bag at the station B. The bag provides an open upper end, as indicated in Figure 23, into which the inside tucking fingers 364 and 364' enter. The outside tucking fingers 366 take corresponding positions outside the bag. Upon engagement of the trips 380 and 380' with the trip members 398 and 400, the spring actuated cams 372, 372' and 374, 374' effect a snap action rotation of the corresponding pivot shafts to move the pairs of tucking fingers into overlapping positions, as indicated in Figures 24 and 27. In this way, a "gusset" is formed at the top of the bag.

While the tucking fingers are in the positions shown in Figures 24 and 27, the bag is heat pre-sealed by a pair of corrugated-edge heater jaws 408 and 410 having electric heating elements 409 and 410. Preferably, the elements 409 and 410 are of about 180 watt capacity to provide a sealing temperature within the range of 200° to 300° F. As clearly seen in Figures 20 and 24, the heater jaws are positioned at an operative height so as to engage the bag immediately below the formed gusset and the tucking fingers. When the seal has been formed the tucking fingers may be withdrawn from the bag and reset to their normally spaced position for performing the next bag tucking operation. As the carriage 330 is moved upward to remove the tucking fingers from the

11

bag following completion of the tucking and heat pre-sealing operation, the reset rollers 402, 402' engage the bottom edge of the reset plate 406 and are held against further elevation. As the carriage 330 continues to move further upwardly, the arms 404, 404' are rotated so as to effect clockwise and counter-clockwise rotation, respectively, of the pivot shafts 368 and 368'. It will be apparent that in this way the cams 372 and 372a of the tucker assembly are rotated to positions again permitting locked engagement of the latch levers and pairs of cams as seen in Figure 25. The elements are then reset and in proper position for another tucking operation upon lowering of the carriage 330.

The operation of the heat pre-sealing means, which operates in cooperation with the tucking mechanism, will now be described in detail with particular reference to Figures 19 to 22. A sleeve 412 is carried in freely rotatable manner on the shaft 350, and provides a pair of arms 414 integral therewith for rotatably supporting a cam roller 416. The roller 416 cooperates with an inside heater cam 418. A collar 420 is fixedly secured to the shaft 350 for positioning the sleeve 412 in predetermined position against the carriage actuating arms 348 (as best seen in Figure 21). A lever 422 extends integrally from the sleeve 412, and is pivotally connected to a link assembly 424, which is in turn pivoted to the rearward end of a heater slide bar 426. The bar 426 mounts the heater jaw 408 at its forward end upon a support bracket 428. A compression spring 430 is positioned intermediate the main channel 18 and a flange portion 432 of the heater slide bar 426 for urging the bar 426 in a rearward direction. The link assembly 424 comprises a pair of yoke members rigidly secured together by means of a bolt and slot 434, so as to be adjustable in length to permit the predetermined position of the heater jaw 408 to be varied, if required by the particular material thickness of the bags being sealed.

An outside heater cam 440 is carried by the cam power shaft 300, and cooperates with an internal cam roller 442 rotatably carried by an integral arm 444 of a sleeve 446. The sleeve 446 is freely rotatable on a horizontal shaft 448 which is fixedly carried by the template 334. A lever 450 extends integrally from the sleeve 446, and is pivotally secured at its lower end to an upper rack member 452. The rack 452 cooperates with a pinion 454 carried by a shaft 456. Reciprocation of the upper rack 452 effects rotation of the shaft 456 and a pair of second pinions 458 and 459 carried thereby. A pair of lower racks 460 and 461 mesh with the pinions 458 and 459, and are thereby reciprocated in accordance with rotation of the sleeve 446.

The lower racks 460 and 461 carry at their forward ends a heater support bracket 462 which serves to mount the heater jaw 410. A biasing spring 464 serves to provide a sealing force between the cooperating corrugated edges (see Figure 24) of the heater jaws 408 and 410 when the bar 426 and racks 460, 461 are moved in opposite directions toward each other to effect engagement of the heater jaws with a bag therebetween. In this way, a "floating" mounting of the jaw 410 is provided, and the sealing force of the engaged heater jaws may be adjusted in accordance with the requirements of the particular bag material.

In practical operation the inside and outside heater cams 418 and 440 are designed for timed cooperation with the rotation of the tucker lift cam 356, so as to effect a sequential operation upon a bag at the station B, whereby the bag is tucked, heat pre-sealed, and released. The sealing force provided by mechanical movement of the heater jaws 408 and 410 into engagement with each other by reciprocation of the members 426 and 460, 461, in cooperation with the adjusting force of the spring 464, and the duration of the time of the engagement of the heater jaws serve to enable a care-

12

ful selective adjustment of sealing conditions for satisfying the requirements of particular bag materials.

The series of operations heretofore described at station B are completed during the time of a single indexing dwell period of the main conveyor 150. The conveyor next carries the bags by indexing movements to station C where they receive a second or intermediate heat sealing operation. The first heat pre-sealing at station B occurs at a level along the bag height which is at the lower end of the gussets, and, although this heat pre-sealing serves to maintain the formed gussets, there is a tendency for the portion of the bag thereabove to "butterfly" outwardly. The bag at this stage, therefore, has a flared upper end, which is not desirable during the label-applying operation to be thereafter performed. Accordingly, an intermediate heat sealing operation is effected at station C.

As best seen in Figure 28 of the drawing, the operating mechanism at station C comprises a heater bar support bracket 470 which carries an outer heater jaw 472. The bracket 470 is directly coupled to the heater operating mechanism of station D, as will hereinafter be described. By coupling the operation of the intermediate heater mechanism of station C with the label-sealing operation of station D, the necessity for separate actuating cams and related structure is avoided, thereby simplifying the construction of the machine and avoiding unnecessary duplication of parts.

An inner heater jaw 474 is carried by a support bracket 476 which is also directly coupled to the feeder operating mechanism of station D by means of a bracket 475. The inner heater jaw 474 is spring mounted at 478 to permit adjustment of the required sealing pressure. The heater elements of the jaws 472 and 474 are preferably of the same heating capacity as those for the jaws at the tucking station, or about 180 watts to provide a sealing temperature of 200° to 300° F.

During the dwell period of the main conveyor 150, the jaws 472 and 474 are brought into engagement with each other for effecting further heat sealing above the initial pre-seal line to close the flared upper end of each bag preliminary to the application of a header label. Upon separation of the intermediate heater jaws 472 and 474, the bags are moved to station D by the indexing operation of the main conveyor 150.

At station D, a header label is bent over the top of the bag and heat-sealed thereto. The mechanism for performing this operation will now be described in detail, particular reference being had to Figures 28 through 37 of the drawings. A label unit body 480 (sec Figure 28) is fixedly mounted upon the main channel 18 by means of a flange bearing 482 and related bracket structure. The body 480 serves to carry a pair of vertical slide gibs 484 and 485, the gib 484 being fixed and the gib 485 being adjustable. A carriage 486 for a combined label picking and folding unit is mounted for vertical sliding movement within the gibs 484 and 485. A turn-buckle 488 is pivotally connected at its lower end to the upper end of the carriage 486, and provides an adjustable connector linkage with a pair of label cam arms 490 to which it is pivotally connected at its upper end (see Figure 29).

The arms 490 are freely rotatable on a suitable bushing sleeve carried by a fixed pivot shaft 492. A mounting sleeve portion 494 of a support post 495 (see Figure 30), which carries the flange bearing 482, and a brace member 496 fixedly bolted to an integral boss portion 497 of the post 495, serve to support the pivot shaft 492. A sleeve 498 positions the arms 490 in spaced parallel relation for rotation upon the pivot shaft 492.

A cam roller 500 is carried between the spaced arms 490 intermediate their lengths for cooperation with a label slide cam 502. The cam 502 is mounted for driving rotation upon the shaft 300. A tension spring 504 is secured to the arms 490 and a fixed frame element

carried by the channel 18 by means of an anchor pin 506 and a bolt 503. Rotation of the power shaft 300 operates to effect oscillation of the arms 490 and thereby vertical reciprocation of the carriage 486. The spring 504 normally biases the carriage 486 in a predetermined lowered position.

The carriage 486 provides a horizontal rotatable spindle 510, which fixedly carries a label picker frame 512 (see Figure 34). The frame 512 provides a head 514 at its lower forward end. The head is of generally hollow form having a plurality of suction cups 516 spaced along its forward face. The cups communicate inwardly through the head 514 with a suction line connection 518 adapted to be connected to a reduced pressure line 519. A pair of cam rollers 520 and 521 are carried by the frame 512, and cooperate with a pair of vertically disposed cam plates 522 and 523 carried by the body 480. A compression spring 524 (see Figure 32) is positioned between the frame 512 and the carriage 486 for exerting a biasing force tending to swing the frame 512 upwardly and outwardly about the spindle 510.

A label folder 526 having a generally horizontal engagement bar 528 is pivotally mounted at the lower end of the frame 512 by means of a pair of spindles 530. A pair of cam rollers 532 and 534 are carried by the folder 526. A tension spring 536 is connected to the upper end of the frame 512 and to the folder engagement bar 528, serving to exert a biasing force tending to pivot the folder 526 in a clockwise direction as seen in Figure 32. A pair of folder actuators 538 are carried by the body 480 for cooperative engagement with the rollers 532 and 534.

A magazine unit is positioned immediately forwardly of the label picker frame 512 to provide a continuous source of header labels. The magazine unit (see Figures 28 and 29) comprises a downwardly inclined right angle channel 540 having a cooperating adjustable side wall 542. Suitable lock rods 544 permit positioning of the side wall 542 in accordance with the size of the labels being employed. A support bracket 546 and related supporting structure serves to permit adjustable positioning of the magazine unit relative to the labeling unit in fixed mounted manner upon the channel 18. A feeder block 548 is slidable within the inclined channel for exerting a forward feeding pressure, and may be provided with a supplementary spring bias, if desired. A pair of resilient retainer arms 550 are carried by the channel 540 and side wall 542 at the outlet end for retaining a stack of labels L within the magazine until removed by the label picker mechanism.

Heat sealing means are provided at the labeling station D for effecting an attachment of a header label to the sealed bag top after it has been folded over both sides of the upper end of the bag. The heater means comprise reciprocating inner and outer heater jaws, substantially the same manner as the heater means at the tucking station B. As best seen in Figures 28 and 29 of the drawing, an inside heater cam 560 is mounted for rotation by the cam power shaft 300. A cam roller 562 rides upon the cam 560, and is rotatably carried by an integral arm portion 564 of a sleeve 566. The sleeve 566 is freely rotatable upon the fixed pivot shaft 492, and provides an integral lever 568 which extends downwardly therefrom in an angularly offset manner (see Figure 30). The lever is pivotally connected at its lower end to a pair of links 570, which are in turn pivotally connected to the rear end of a heater slide bar 572. The bar 572 is supported for sliding movement across the main channel 18, and carries a heater support bracket 574 at its forward end. The bracket 574 provides a mounting for an inside heater jaw 576. A bracket portion 578 of the lever 568 provides an abutment for a compression spring 580, which engages at its other end the support post 495. In this

way, the lever is biased so as to retain the cam roller 562 in engagement upon the cam 560.

An outside heater cam 582 is mounted for rotation by the power shaft 300. An internal cam roller 584 cooperates with the cam 582, and is rotatably carried by an integral arm portion 586 of a sleeve 588. The sleeve 588 is freely rotatable upon the shaft 448, which terminates within a support boss 590 of the post 495. An integral lever 592 extends downwardly from the sleeve 588, and is pivotally secured to a transverse link 594, which is in turn pivotally secured to an integral arm portion 596 of a sleeve 598. The sleeve 598, and a complementary sleeve 600, are fixedly secured to a shaft 602 (see Figure 32). The shaft 602 is mounted for rotation within bearing portions of a pair of gear housings 604 and 606. The housings enclose a pair of pinions 608 and 609 which cooperate with a pair of racks 610 and 611. The racks fixedly carry a pair of heater slide bars 612 and 614, which are mounted for transverse reciprocation across the main channel 18 by means of a pair of slide guides 613 and plates 615.

A heater support bracket 616 is mounted across the forward ends of the slide bars 612 and 614. An outside heater jaw 618 is mounted upon the bracket 616, and is spring biased at 620. Heating elements 622 and 624 are embedded within the heater jaws 576 and 618. Preferably, the heater elements for the labeling station sealing means are of a greater heat capacity than those at the pre-seal and intermediate-seal stations. In practice, a greater sealing temperature is required because of the material thickness of the label, and elements of 180 watts are employed to provide a sealing temperature in the range of about 360° to 450° F.

The intermediate station C heater bar support brackets 470 and 475 are carried by the brackets 616 and 574 (see Figure 28). In this way, reciprocation of the heater support brackets 616 and 574 also effect reciprocation of the intermediate station C heater support brackets 470 and 475.

During the period of indexing dwell of the main conveyor 150, a bag at the labeling station D is provided with a header label which is folded over and heat sealed. The various operating cams provide a timed sequence of operations performed in substantially the following manner. The carriage 486 of the label picking and folding unit slides vertically downwardly in response to the rotation of the label slide cam 502 and the force of the spring 504. In Figures 35 through 37 of the drawing, the sequence of operating movements have been illustrated. The cam rollers 520 and 521 of the label picker frame 512 ride along the cam surfaces provided by the plates 522 and 523. The cooperation between these parts serves to pivot the frame 512 about the spindle 510 in a rearward direction. As the carriage 486 moves downwardly, the label picker head 514 assumes a position of contacting engagement against the lead label L of the label feed mechanism. The suction cups 516 are subjected to a vacuum pressure and serve to draw the lead label into tightly held engagement against the head.

As the carriage 486 continues to move downwardly, the pivoting frame 512 withdraws the head 514 away from the label magazine with a single label carried thereby. The cam rollers 532 and 534 of the label folder 526 next engage the folder actuators 538, and effect a pivoting of the folder bar 528 against the upper end of the header label (as seen in Figure 36). Continued downward movement of the carriage 486 effects further pivoting of the label folder 526 so as to bend the label into two half portions positioned at opposite sides of the sealed bag top (as seen in Figure 37).

The heaters 576 and 618 are then brought into sealing engagement at opposite sides of the folded label L, and serve to effect an initial heat sealing of the label against the upper end of the bag. The heater jaws are then separated, the vacuum suction within the head 514 is

released, and the carriage 486 is withdrawn to its upper position for the next label picking and folding operation.

The main conveyor 150 next carries the bags by indexing movements to the final sealing station F, where the header label and sealed bag top are provided with a complete and high strength final seal of substantial vertical height. For this purpose, a final seal operating cam 630 is mounted for driving rotation by the cam power shaft 300 (see Figure 38). A cam follower roller 632 is mounted for rotation upon a shaft 634 disposed within an upper recess 636 of a slide block 638 disposed below the cam 630. The block 638 is mounted for vertical reciprocation within a slide guide housing 640. A pair of actuator rollers 642 and 644 are mounted for rotation upon shafts 643 and 645 within a lower recess 646 of the slide block 638. An outside heater wedge 648, and a longitudinal bar portion 649 integral therewith, cooperate with the roller 644. An outside heater slide bar 650 is rigidly secured to the wedge bar 649. A heater support bracket is carried by the slide bar 650 at its forward end, and serves to mount an outside heater jaw 654 in a resilient manner by means of spring 655. The jaw 654 provides a sealing surface of substantial vertical height. A compression spring 656 is positioned between the wedge 648 and an abutment bracket 658. An adjusting screw 660 is provided for varying the loading force of the spring 656.

An inside heater wedge 662, having a transversely elongated bar portion 664 integral therewith, cooperates with the roller 642. A pair of slide bars 666 and 668 (see Figure 39) are rigidly carried by the wedge bar portion 664. A support bracket 670 is carried by the slide bars 666 and 668 at their forward ends, and serves to mount a heater jaw 672. The jaw 672 provides a sealing surface of substantial vertical height for cooperating engagement with the jaw 654. Guide housings 674 and 675 serve to retain the slide bars 666 and 668 for sliding movement transversely across the main channel 18. Spring housings 676 and 677 are rigidly carried by the guide housings 674 and 675 and provide compression springs 678 and 679 which engage the inside heater wedge bar portion 664.

Heating elements 680 and 681 are provided for the jaws 654 and 672, respectively, and are preferably of about the same heat capacity as those of the jaws at the labeling station D. In practice, elements of 180 watts are employed, and a temperature range of about 360° to 450° F. is provided.

It will be apparent that the spring 656 and the springs 678, 679 serve to urge the respective wedges 648 and 662 into engagement with the corresponding actuator rollers 642 and 644. The inclined engagement surfaces of the wedges transmit the spring forces through the rollers to the slide block 638, thereby biasing the block upwardly to effect engagement of the cam follower 632 against the cam 630. Rotation of the cam 630 serves to effect lowering of the slide block 638 against the bias of the wedge springs, so that the rollers 642 and 644 operate to increase the spacing distance between the wedge blocks and thereby move the heater jaws toward each other into sealing engagement. As the cam 630 rotates to permit the slide block 638 to return to its upward position, the wedges move toward each other to a return position and the heater jaws are separated. In this way, a timed reciprocation of the heater jaws is controlled by the cam 630.

As seen in Figure 39 of the drawing, the dating station G, to which the bags are moved by the indexing conveyor after the final sealing operation at station E, includes a dater slide bar 682. A slide guide 684 is provided by the support bracket 304 (see Figure 4). A printing head 686 is carried by the slide bar 682 at its forward end, and cooperates with a fixedly positioned abutment block 688. A connector bracket 690 secures the slide bar 682 to the slide bar 668 of the final sealing

station E. In this way, reciprocation of the final sealing heaters also effects reciprocation of the dater slide bar, thereby eliminating the necessity for unnecessary duplication of operating parts. The printing head 686 serves to apply a date or code designation to each completed sealed bag prior to discharge from the machine.

A continuously driven discharge conveyor 692 is provided at the discharge end of the machine for removing the completed sealed and labeled bags (see Figure 1). The discharge conveyor 692 includes a continuous belt 693 (see Figure 3) supported by a driver pulley 694 and a cooperating driven pulley 695. The driver pulley 694 is rotated by a drive shaft 696. A driven sprocket 698 is carried by the drive shaft 696 for transmitting driving power to the conveyor.

As clearly seen in Figure 1 of the drawing, an Idle Station E is provided intermediate the Labeling Station D and the Final Sealing Station F. The Idle Station E serves to provide a movement delay in the forward feed of bags through the machine, thereby permitting a more efficient spacing of the various operating mechanisms of the machine. A pair of timing cams 700 and 702 (see Figures 1, 2, and 28) are carried by the shaft 300 at the Idle Station E. These cams are component parts of a timing mechanism for actuating and controlling the removal of header labels L from the label magazine prior to folding and attachment to the bags. The operation of the entire timing mechanism will be hereinafter described in detail in connection with the electrical control circuit of the machine.

As indicated more or less diagrammatically in Figure 3, each of the cams 700 and 702 cooperates with a roller 704 supported by a pivot arm 706. Each arm 706 is pivoted to a fixed axis at its end opposite the roller 704, and rests upon the actuator plunger of a corresponding microswitch indicated at 708 and 710 in Figure 2. It will be apparent that the timing cams 700 and 702 are continuously rotated by the power shaft 300, and thereby effect a cyclical opening and closing of the microswitches 708 and 710.

As best seen in Figures 13 and 16, a trip plate 712 is pivoted to a fixed bracket 714 below the top plates 16 so as to extend upwardly therethrough in alignment with the path of bag movement between the Tucking Station B and the Pre-Seal and Labeling Stations C and D. Passage of a bag over the trip plate 712 serves to effect a downward pivotal movement thereof for cooperation with the plunger of a microswitch 716. In this way, the movement of a tucked and pre-sealed bag toward the labeling station effects a closure of the microswitch 716.

The mechanical drive for the machine will now be described, and particular reference for this purpose is made to Figure 3 of the drawing. A motor M, of $\frac{3}{4}$ H. P. or similar capacity as required by the size of the machine, transmits driving power through its drive shaft 720 and a belt 722 to a horizontal cross-shaft 724 of the gear reducer 326. Driving power is transmitted from the gear reducer 326 to the vertical shaft 312, which in turn effects drive of the main power shaft 300 for actuating the various bag closing and labeling operations, and the Geneva mechanism 320 for effecting indexing drive of the main conveyor 150.

A power chain 730 is also driven by a vertical shaft of the gear reducer 326, and serves to transmit driving power to the inlet and discharge conveyors, and to the bag loading mechanism of station A. The chain 730 effects continuous drive of a vertical power shaft 732 positioned adjacent the inlet conveyor 50, a vertical power shaft 734 positioned adjacent the discharge conveyor 692, and a vertical power shaft 736 adjacent the bag loading mechanism. A sprocket 738 is carried by the shaft 732, and transmits power through a chain 740 to the vertical inlet conveyor belts 66 and 68. A bevel gear 742 is carried by the shaft 732, and drives a co-

operating bevel gear 744 for rotating a sprocket 746, thereby driving a chain 748 which transmits power to the horizontal inlet conveyor belt 54. The chain 748 drives a sprocket 749 and a second chain 750 to transmit driving power to a lubricator pump 752. In this way, lubricating fluid may be provided as desired to various points of the machine continuously when the motor M is energized.

The vertical shaft 734 transmits power through a gear box 754 to a sprocket 755, thereby driving a chain 756 which actuates the discharge conveyor belt 693.

The vertical shaft 736 carries a cam 760 for actuating the operation of the bag feeding mechanism at station A. As best seen in Figures 3a and 14 of the drawing, the bag feed operating mechanism includes a lever arm 764 pivotally secured to the machine frame 10 at its one end, and providing an integral vertical post 766 at its free end. A cam roller 762 is carried by the arm 764 intermediate its ends for cooperation with the cam 760. A tie rod 768 is pivotally secured at its one end to the upper end of the post 766, and at its other end to a bracket 770. The bracket 770 is rigidly secured to the slider bar 108 which carries the pusher plate 100. A spring 772 is secured to the machine frame and to the bracket 77 to exert a biasing force tending to move the bracket 77 and the pusher plate 100 toward the main indexing conveyor 150.

A latch arm 774 is pivotally carried by a bracket 776 fixed to the machine frame 10. The latch 774 provides a lock shoulder at its free end for cooperation with a roller 778 which is carried below the arm post 766. It will be apparent that when the roller arm 778 is seated against the latch 774, the biasing force of the spring 772 will serve to position the arm 764 in fixed orientation relative to the cam 760. The parts are arranged so that when the latch 774 engages the arm roller 778, the cam roller 762 is positioned out of engagement with the high portion of the cam 760. In this way, rotation of the cam 760 does not effect any movement of the arm 764. A pair of connector straps 780 are pivotally secured to the latch 774 and to a plunger 782 of a solenoid device 784. A spring 786 is secured to the strap 780 and to a fixed point on the machine frame 10 so as to normally exert a force tending to maintain the latch 774 in engagement with the arm roller 778.

When the solenoid 784 is energized, the plunger 782 will be withdrawn so as to effect a pivoting of the latch 774 away from the arm roller 778. The spring 772 serves to effect a movement of the arm 764 to bring the roller 762 into riding engagement with the surface of the cam 760. The cam 760 is then operative to control swinging movement of the arm 764 in response to the force of the spring 772, and thereby to control reciprocation of the tie rod 768, bracket 770 and slider bar 108. In this way, the pusher plate 100 remains in fixed position until such time as the solenoid 784 is energized to render the actuating mechanism operative in response to the cam 760 for effecting reciprocation of the plate 100.

As clearly seen in Figure 3, manual means are provided for effecting rotation of the sprockets 34, to enable rotation of the elevator screws 24 for raising and lowering the support channel 18 relative to the top plates 16 of the machine. A manual crank 790 cooperates with a cross shaft 791 to drive a pair of bevel gears 792, and thereby drive a chain 794 which is meshed with the sprockets 34.

Manual means are also provided for effecting drive of the gear reducer 326, and thereby rotate the shaft 312 and drive the chain 730. For this purpose, a manual crank 796 having a hollow stub end 798 may be inserted through the machine frame to receive a cross shaft 800 in non-rotatable relation for effecting a rigid interconnection. The cross shaft 800 carries a sprocket 802 which meshes through a chain 804 with a second sprocket 806 carried by the gear reducer shaft 724. In

this way, rotation of the hand crank 796 effects manual drive of the main power system of the machine.

As shown in Figure 41, a safety interlock is provided upon insertion of the crank stub end 798 onto the cross shaft 800. A microswitch 810 is engaged by the shaft stub 798 when it is positioned in rigid interconnection with the cross shaft 800. The microswitch 810 provides a safety interlock when actuated by attachment of the crank 796 as will be hereinafter described in connection with the electrical operating circuit of the machine. In no event can the crank 796 be power driven by the motor M so as to endanger operating personnel.

The electrical control circuit for the machine will now be described with particular reference being made to Figure 40. The control circuit comprises a pair of main power leads 820 and 822, suitably connected to a current supply. A conductor line 824 extends across the leads 820 and 822. A machine "stop" switch 826, preferably of the push button type, is provided in the line 824 for opening the circuit therethrough. A conductor line 828 extends across the line 824 and the lead 822. A motor "start" switch 830, preferably of the momentary-contact push-button type, is provided in the line 828 for effecting energization of the machine motor M. When a circuit is completed through the line 828 by closure of the start switch 830, a relay control switch 832 will be held closed to maintain energization of the motor M. When the circuit is opened by manual actuation of the stop switch 826, the relay control switch 832 will return to a circuit open position, thereby de-energizing the motor M. A normally-closed overload switch 834 is provided in the line 828 for safety purposes, and serves to effect opening of the circuit in the event of an excessive current flow through the line 828. It will be apparent, therefore, that the motor M will not be energized until the start switch 830 is manually closed by the machine operator. Thereafter, the relay controlled switch 832 will maintain a closed circuit, and the motor M will continue to provide driving power for the machine until such time as the circuit is opened by the relay controlled switch 832 in response to manual actuation of the stop switch 826.

A pump "start" switch 836 of the momentary-contact type is provided in the line 824, and serves to energize a relay controlled switch 838 to maintain energization of the vacuum pump 837 in the same manner as the switch 832 controls the motor M. It will be apparent that the circuit through line 828 is not closed to energize the motor M until the relay controlled switch 838 has been closed. In this way, the pump 752 must be separately actuated to provide a continuous lubricant supply to the machine before the motor M can be energized by the start switch 830. Both the motor and pump will continue to operate until such time as the stop button 826 is manually actuated to de-energize both the motor M and the pump 752. A normally closed overload switch 840 is also provided in the line 824 between the pump and the power lead 822 for safety purposes in the same manner as switch 834.

A conductor line 842 extends between the line 824 and the power lead 822 in series with the switches 826 and 836. A conductor line 844 extends across the line 842 and the lead 822. The normally-open bag loader microswitch 120 (station A) is positioned in the line 844. The normally-closed timer cam actuated microswitch 708 is positioned in the line 844 in series with the switch 120. The latch solenoid 784 (Figure 3a) is positioned in the line 844 directly in series with the switches 120 and 708. In this way, the latch solenoid 784 is energized to effect actuation of the bag loader mechanism at station A only when both of the switches 120 and 708 are simultaneously closed. This condition will occur when the inlet conveyor 50 has delivered a bag into engagement with the stop plate 102, so as to effect a pivoting thereof to close the microswitch 120.

The bag loading mechanism will then be operated in timed response to the timer cam 700 which opens the normally-closed switch 708 during indexing movement of the main conveyor 150. In this way, a bag is fed by the reciprocating pusher plate 100 only when a bag is present at the station A and the conveyor 150 is dwelling.

A solenoid 846, for regulating the operation of a valve to communicate the suction line 519 of the label picking mechanism (station D) to the vacuum source 837 is positioned in the line 842. Energization of the solenoid 846 serves to provide the label picker head with the necessary suction for removing labels from the magazine unit preparatory to folding and sealing such a label over a bag. The normally-open cam actuated microswitch 710 is in series with the solenoid 846 in the line 842. The bag trip plate actuated microswitch 716 (Figure 16), also normally open, is positioned in parallel with the switch 710 across the line 842. Closure of either of the switches 710 and 716 will serve to energize the suction valve control solenoid 846. The times of closure of the respective switches 710 and 716 are carefully predetermined so as to insure withdrawal of a label from the magazine by the picker head only when a bag is being delivered to the labeling station, and only in coordinated sequence with the reciprocating movement of the folding mechanism.

As a bag moves toward the labeling station D, it will pass over the trip plate 712 and effect a closure of the normally-open microswitch 716. This will serve to energize the solenoid 846 and provide vacuum for the picker head cups 516. The solenoid 846 will remain energized until the bag has passed beyond the trip plate 712 and the microswitch 716 is again opened. During the time that a bag is passing over the trip plate 713 the picker head will be passing directly opposite the label L of the magazine and will operate in response to the vacuum supply to grasp the lead label and effect its removal from the magazine. Just as the picker head is about to pass beyond the magazine feed mouth, the timer cam 702 will operate to close the switch 710, thus insuring a continuing supply of vacuum for retaining gripping engagement of the label by the picker head. The timer cam 702 will maintain the switch 710 closed for a sufficient time to permit the completion of the label folding and sealing operation at station D. The solenoid 846 will then be de-energized, and the vacuum will be released.

It will be apparent that the timer cam 702 is always operative to actuate the vacuum supply to the picker head in a cyclical manner with each reciprocation of the picking and folding mechanism. The point at which the timer cam 702 closes the switch 710 is arranged so that the suction cups 516 of the head are just beyond the required position for effecting gripping of the lead label when vacuum is supplied. It is only the trip plate actuated microswitch 716 which is operative to effect energization of the solenoid 846 for supplying vacuum at the proper instant when the picker head cups are immediately opposite the lead label at the magazine feed mouth. As a bag moves toward station D, the switch 716 provides vacuum for grasping a label, after which the timer cam 702 takes over to close the switch 710 and maintain the vacuum supply during the folding and sealing operation. If no bag is carried over the trip plate 712 by the conveyor 150, the vacuum controlled by the switch 710 is "too late" to effect a picking off of a label from the magazine. The labels, therefore, are only removed from the magazine as required in response to feeding movement of bags through the machine.

Conductor line 848 extends across the power leads 829 and 822. A double-throw manual switch 850 is provided in the line 848 for effecting manually regulatable energization and de-energization of the sealing bar heater elements at stations B, C, D, and E. The conductor line 848 branches into five conductor lines 854 to 862, all in

series with the line 848 and lead 822. A red light 864 or similar signal device is positioned in the line 854, and is energized when the heaters are energized. A first timer motor 866 and a second timer motor 868 are positioned in the lines 856 and 858, respectively. It will be understood that electrical thermostat or transformer devices may be used in place of the timer motor means. The timers 866 and 868, when energized, serve to cyclically close a pair of corresponding normally-open switches 870 and 872 in the lines 860 and 862. The heating elements for the sealing bars at each of stations B and C, indicated collectively in Figure 40 as B and C-H. E., are connected in series with the switch 870. The sealing bar heating elements for stations D and F, designated as D and F-H. E., are similarly connected with the switch 872. Amber lights 874 and 876, or other suitable signal devices, are positioned in the lines 860 and 862 so as to be energized when the heaters are being energized. In this way, the heating elements are periodically energized by the timers 866 and 868 so as to maintain a constant predetermined heating temperature. Adjustment of the cycling speed of the timers 866 and 868 serves to enable selective adjustment and maintenance of the sealing temperatures of the inner and outer sets of heating elements.

The normally-closed safety interlock microswitch 810 is positioned in the circuit in the line 828. It will be apparent that when the crank 796 is coupled to the shaft 800 for manually driving the machine, the microswitch 810 will be engaged and opened, thereby breaking the circuit 30 through line 828. In this way, the motor M cannot be energized.

In Figure 42 of the drawing, we have illustrated a modified label magazine structure. In practice, it is common to employ labels which are scored or perforated along a center line to facilitate folding during the labeling operation. For example, the label seen in Figure 34 is scored at 889. Such scoring or perforating results in an irregularity or "bump" in the surface of at least one side of the label. When a large number of labels are stacked together in a magazine, the scores or perforations of the labels have a cumulative effect tending to arc or curve the lead labels at the feeding mouth or outlet end of the magazine. Despite the application of a substantial and uniform pressure by a feeder block or the like, the lower edges of the labels tend to "drag." As a result, the forward labels are substantially bowed or bent so that the surface area of the lead label which is presented to the suction head of the label picker mechanism may be too small and insufficiently planar in contour to permit effective gripping by the suction cups 516. As a result, there may be frequent failures in label removal from the magazine, and the bags which are delivered at station D will not be labeled. This difficulty is particularly encountered when labels of substantial material thickness are employed. Relatively heavyweight cardboard header labels are desirable for certain packages, and it is therefore highly important in the operation of the bag header machine of this invention to obviate this particular problem.

Accordingly, a modified form of magazine unit may be utilized in place of the inclined gravity feed unit heretofore described. The modified label magazine of Figure 42 provides a continuous traveling belt 882 mounted for driving movement by a relatively large diameter driver pulley 884. The forward end of the belt 882 is held taut for sliding movement over a relatively narrow leading edge 886. The top surface of the belt 882 provides a downwardly inclined traveling support upon which the labels L are adapted to rest in stacked relation. A pair of elongated side guides 888 serve to engage the sides of the labels and hold them in aligned relation on the belt 882. Transversely adjustable support brackets 890 and 892 permit selective positioning of one of the guides 888 for accommodating labels of various widths. A plurality of lateral support rollers 894 are provided to maintain the traveling surface of the belt 882 in rela-

tively level relation for supporting the labels L. Resilient retainer arms 896 are carried by one of the guide support brackets 892, and provide means for retaining the upper edges of the labels in predetermined retained position at the outlet or feeding mouth of the magazine. Side retainer clips 898 are carried by the side guides 888 for similarly positioning and retaining the side edges of the labels. A feeder block 900 provides a force serving to urge the stack of labels L forwardly toward the outlet end of the magazine. Suitable supporting structure, not shown in detail, is contemplated for positioning the magazine unit relative to the label unit in fixed mounted manner upon the channel 18, so as to permit adjusting movement when the various operating parts of the machine are oriented for bags of a particular size.

A drive arm 902 is fixedly pinned to a shaft 904 of an over-running clutch 905 which rotatably carries the driver pulley 884. The arm 902 is pivoted by means of a lost motion slot 903 to a connector link 906, which is in turn pivotally secured to the outside heater support bracket 616 at station D. As the heater jaws at station D are reciprocated toward and away from each other to effect heat sealing operations, the link 906 is reciprocated in a corresponding manner. Such reciprocation effects a relatively lesser movement of the arm 902 in an arcuate path. Such swinging movement of the arm 902 is still further reduced in terms of the rotative movement of the shaft 904, resulting in a relatively small angular movement of the clutch 905. In this way, small increments of forward movement of the belt 882 are effected. For example, the parts may be arranged so that $\frac{3}{8}$ inch movement of the link 906 provides $\frac{1}{8}$ inch swinging of the arm 902 and consequent angular movement of the clutch 905 to provide a forward belt travel of about $\frac{1}{32}$ inch.

Appropriate adjustment of the over-running clutch 906 may be made to accommodate labels of various thicknesses, so that a distance of belt travel substantially greater than the thickness of one label will be effected upon each cycle of reciprocating movement of the heater bars. In this way, the bottom edges of the labels L are intermittently fed forwardly with each movement of the heater jaws away from each other. Upon a return stroke of the link 906 as the heater jaws move toward each other for effecting a sealing operation, rotation of the arm 902 causes the clutch 905 to overrun, so that there is no return motion of the belt 882. By maintaining the bottom edges of the labels in a positively forwardly fed position at the discharge end of the magazine, a sufficiently large flat surface is always presented by the lead label to the suction cups 516 of the label picker mechanism, thereby insuring withdrawal of a label whenever the picker mechanism is actuated and provided with the necessary suction in response to timed bag feeding movement to station D.

When the labeling mechanism cycles, it will be apparent that the belt will continue to index forwardly by substantial increments, and will effect slippage with the label bottom edges due to their retention in the magazine by the fingers 896 and 898, thereby insuring maximum forward alignment of the labels.

In Figure 43 of the drawing, a timing chart is provided to show the relationship between the positions of movement of the various actuating cams and operating elements of the machine. It will be understood from the foregoing description and the timing chart of Figure 43 that the operating elements of the machine are carefully coordinated and timed to effect the performance of each of the series of consecutive machine operations in an accurate and precise manner.

Summary of practical operation

The detailed operation of the machine may be summarized as follows. At the feed station A, a bag of thermoplastic material which has been previously filled with its contents (cellophane bags with double stacks of

round cookies having been illustrated by way of example) is transferred from the inlet conveyor to a position between an adjacent pair of bag pushers of the main indexing conveyor. This bag feed is actuated in timed response to the presence of a bag at the feed station and the dwelling of the main conveyor.

The bag is then indexed to the tucking station B, where the tucking mechanism descends to position the tucking fingers inside and outside of the bag at both sides. At the end of the downstroke of the tucking fingers, which are spring loaded, the fingers are tripped and the gussets are formed. The first heat sealer bars then close on the bag just below the tucking fingers, holding the bag while the tucking fingers are withdrawn and sealing the tucked gussets in place. The tucking fingers are automatically reset for the next operation as they are withdrawn.

The bag is then indexed to the pre-seal station C, where the pre-seal heater bars, which are actuated by an extension of the outer label sealer bar at station D, operate to tack-seal the top of the bag so that the loose ends otherwise present above the first seal will not interfere with the application of the label. The base of the bag then actuates a limit switch which causes a supply of vacuum to enable a label to be withdrawn from the magazine by the label picking and folding mechanism for application to that same bag. If no bag is present at the pre-sealing station at a given cycle, the vacuum system is interrupted so that no label is withdrawn for that cycle.

The bag is then indexed to the labeling station D, where a label has been withdrawn from the magazine by the suction head as it is reciprocated downwardly. The label is folded over the upper end of the bag and held in position while the heater bars close, thereby sealing the bottom edges of the label to the bag. The label mechanism is then withdrawn upwardly preparatory to the next cycle of operation.

The bag is then indexed to the idle station E, which is provided primarily for readily accessible location of the timing cams and efficient spacing of the various machine operating mechanisms.

The bag is then indexed to the sealing station F, where a pair of relatively wide serrated heater bars clamp across the label and provide a final heat sealing operation.

The bag is then indexed to the dating station G, where a suitable code or other marking as desired is stamped onto the sealed header label. The movable printing bar of this station is an extension of the outside heater bar at station F.

The bag is then delivered in sealed and labeled condition onto the discharge conveyor for removal from the machine.

Changes may be made in the construction and arrangement of the parts of our bag header without departing from the real spirit and purpose of our invention, and it is our intention to cover by the claims any modified forms of structure or use of mechanical improvements which may be reasonably included within their scope.

What we claim as new and desire to obtain by Letters Patent of the United States is:

1. In a bag sealing machine having combined tucking and presealing means operative to form gussets in the open end of a bag and effect presealing of the bag below the gussets, the combination with said tucking and presealing means of labeling means operative to apply and fold a header label over a bag following tucking by said tucking means, label sealing means operatively associated with said labeling means to seal the header label to the bag, and supplemental presealing means intermediate said tucking and presealing means and said labeling means operative to effect a second presealing of the bag above the first preseal.
2. A machine for automatically applying header labels to bags, comprising conveyor means operative to move

tor means responsive to movement of a bag by said indexing conveyor means from said tucking means to said labeling means to render said label providing means operative.

12. In a bag sealing machine, means for applying, folding, and sealing a header label to a bag, said means comprising a label magazine for providing a source of header labels, a vertically reciprocable carriage adjacent said label magazine, a label picker frame pivotally carried by said carriage, said picker frame providing a vacuum head adapted upon reciprocation of said carriage to engage and selectively remove single labels from said magazine, label folder means pivotally carried by said label picker frame and operative upon reciprocation of said carriage to fold a label carried by said vacuum head over a bag upper end, and means for reciprocating said carriage in timed sequence with the presence between said magazine and said carriage of a bag to be labeled.

13. In a bag sealing machine, means for applying, folding, and sealing a header label to a bag, said means comprising a label magazine having a conveyor traveling surface for supporting and aligning a supply of header labels at a predetermined pick-off position, a movable carriage adjacent said label magazine pick-off position, a label picker frame carried by said carriage, said picker frame providing a vacuum head adapted upon movement of said carriage to engage and selectively remove a single label from said magazine pick-off position, label folder means carried by said label picker frame and operative upon movement of said carriage to fold a label carried by said vacuum head over a bag upper end, and means for moving said carriage in timed sequence with the presence between said magazine and said carriage of a bag to be labeled, said traveling surface being intermittently actuated in timed sequence with movement of said carriage to align the labels at said pick-off position.

14. A method of automatically sealing a header label to an initially open-ended bag, comprising the steps of forming gussets in the open end of the bag, presealing the bag below the gussets while they are held in formed relation, presealing the bag over the first preseal, folding

a header label over the bag at opposite sides of said gussets and seals, tack-sealing said label to said bag, and effecting a final sealing of said label and said bag.

15. A method of automatically sealing and header-labeling an initially open-ended bag, comprising the steps carrying the bag to a first station and forming gussets in the open end of the bag, presealing the bag below the gussets at said first station, carrying the tucked bag to a second station and presealing the bag above the first pre-seal, carrying the tucked and double presealed bag to a third station and folding a header label over the tucked bag end at opposite sides of said gussets and seals, tack-sealing said label to said bag at said third station, and carrying said labeled bag to a fourth station and effecting a final sealing of said label and said bag.

16. A method of automatically sealing and header-labeling an initially open-ended bag, comprising the steps carrying the bag to a first station and forming gussets in the open end of the bag, presealing the bag below the gussets at said first station, carrying the tucked bag to a second station and presealing the bag above the first pre-seal, carrying the tucked and double presealed bag to a third station, providing a supply of header labels at said third station, removing a single header label from said supply in response to the presence of the bag at said third station, folding a header label over the tucked bag end at opposite sides of said gussets and seals, tack-sealing said label to said bag at said third station, and carrying said labeled bag to a fourth station and effecting a final sealing of said label and said bag.
